UNITED STATES PATENT OFFICE.

RAYMOND B. PRICE, OF NEW YORK, N. Y., ASSIGNOR TO RUBBER REGENERATING COMPANY, A CORPORATION OF INDIANA.

METHOD OF DRYING MATERIALS.

1,209,643.

Specification of Letters Patent. Patented Dec. 19, 1916.

Application filed February 8, 1913. Serial No. 745,972.

To all whom it may concern:

Be it known that I, RAYMOND B. PRICE, a citizen of the United States, residing in the borough of Manhattan, city of New York, State of New York, have invented new and useful Improvements in Methods of Drying Materials, of which the following is a specification.

My invention relates to the method of 10 drying rubber, and has for its object to not only more rapidly and effectually accomplish this result, but also to do so with a minimum of deleterious effect.

More specifically, my invention relates to 15 the drying of materials by means of a superheated vapor, such as steam.

In the accompanying drawings apparatus is shown suitable for practising my invention, in which drawings:

20 Figure 1 is a longitudinal sectional view through a drier; Fig. 2 is a cross-sectional view taken on line 2—2, Fig. 1; Fig. 3 is a front elevation, partly in section, of a modified form; Fig. 4 is a longitudinal sectional view of a modified form of drier.

Referring to Figs. 1 and 2, 10 designates a closed chamber of any suitable construction in which the material to be treated is disposed, and through which the superheated vapor is passed in such manner as to necessitate its coming into intimate contact with, that is to say, pass through, the body of said material. The chamber has an inlet pipe 11 of any desired size at one end and an outlet pipe 12 at its opposite end, both of which may be provided with area controlling means, such as valves 13 and 14. In the modified form shown in Fig. 3, the chamber 15 is shown to be capable of rotation bodily in order to agitate the material therein during its treatment and in the modified form shown in Fig. 4 the chamber 16 is shown to be provided with interior agitators 17. In the chamber 10 there are trays or shelves 18 for holding the material, and exposing the same to intimate contact with the superheated vapor during its passage through the chamber.

The above described apparatus is particularly adapted to the drying of rubber stock or shoddy in the process of devulcanization of rubber. In this process great economy has been effected by first heating up the stock in the apparatus by the use of wet steam which otherwise would not be used, such as that from the exhaust of engines

and other apparatus. After the stock has been heated up to as high a temperature as possible with wet steam, the superheated steam or other vapor is introduced. This 60 at first causes a mixture of superheated steam and dry steam which afterward results in superheated steam alone coming in contact with the rubber, thereby thoroughly drying it.

The superheated vapor employed may be introduced at atmospheric pressure or at any increased pressure desired. Or by exerting a vacuum upon the chamber the superheated vapor could be admitted at less 70 than atmospheric pressure, as will be readily understood. It will also be understood that the vapor may be introduced at a regulated pressure at one end, and its rate of speed through the chamber be effectually controlled by varying the area of the discharge opening. Or this control of speed may be effected by means of an exhausting apparatus 75 applied to the discharge side of the chamber. A body of material thus subjected to the action of a superheated vapor, such as steam, will be most effectually and rapidly deprived of its contained moisture, either that remaining after draining the stock, or that resulting from condensation 80 of the wet vapor the steam absorbing the same up to its capacity, or, in other words, until saturated, and the rapidity of operation of the process will be dependent upon the speed of the steam, the quantity employed, the temperature and the degree of superheat.

It will be understood that the chamber may be so constructed that the admission and discharge of the material to be treated 95 may be intermittent or continuous, as shown for instance, in Fig. 4 where the rubber is fed through the casing from the hopper 20 and discharged through the outlet 21. The admission and discharge of the superheated vapor, as well as any vacuum or exhaust applied to the chamber, may also be intermittent or continuous.

The chamber employed may be provided with a jacket 22 to more effectually retain 105 the heat therein, and may also be provided with the heating coils 23.

While I prefer to employ a pure superheated vapor during the drying operation, I may, if desired, mix therewith a certain 110 quantity of other dry fluid or gas, such as by mixing steam with air, inert gas or the like,

which may be admitted through the supply pipe 25.

My process may be used for drying rubber wherever moisture is present, but is especially useful for drying rubber waste. The injurious effect of oxidation which is present when the usual drying method is followed, is perhaps more conspicuous in this form of rubber and therefore, greater advantages are attained in this instance from the use of my process, which entirely eliminates any oxidizing action.

Having thus described my invention, what I claim as new and desire to secure by Letters Patent is:

1. The method of treating rubber to prevent its oxidation while drying which consists in enveloping the rubber in a heated non-oxidizing vapor atmosphere for a part of the treatment below the saturation point and for another part of the treatment above the saturation point.

2. The method of treating pulverized re-

claimed rubber to prevent its oxidation and spontaneous combustion while drying which consists in enveloping the rubber in a heated non-oxidizing vapor atmosphere maintained for a part of the treatment below the saturation point and for another part of the treatment above the saturation point.

3. The method of treating pulverized reclaimed rubber to prevent its oxidation and spontaneous combustion while maintaining it in a state of agitation which consists in enveloping the rubber in a heated non-oxidizing vapor atmosphere maintained for a part of the treatment below the saturation point and for another part of the treatment above the saturation point.

In testimony whereof, I have hereunto set my hand in the presence of two subscribing witnesses.

RAYMOND B. PRICE.
